UNITED STATES PATENT OFFICE.

DAVID BAINBRIDGE, OF PHILADELPHIA, PENNSYLVANIA.

MANUFACTURE OF TURNED SHOES.

SPECIFICATION forming part of Letters Patent No. 463,885, dated November 24, 1891.

Application filed June 8, 1891. Serial No. 395,519. (No model.)

To all whom it may concern:

Be it known that I, DAVID BAINBRIDGE, a citizen of the United States, and a resident of Philadelphia, Pennsylvania, have invented 55
5 certain Improvements in the Manufacture of Turned Shoes, of which the following is a specification.

The object of my invention is to make in a simple and economical manner a turned shoe 10 which will be easy to the wearer, the use of tacks in the manufacture of the shoe being obviated and all stitches being concealed, as fully described hereinafter.

I have illustrated in the accompanying 15 drawings an infant's shoe; but it will be understood that my invention is applicable to the manufacture of all turned shoes.

In the accompanying drawings, Figure 1 is a side view of the shoe made in accordance 20 with my invention. Fig. 2 is a plan view of the sole. Fig. 3 is a sectional view on the line 1 2, Fig. 2. Fig. 4 is a sectional view showing the sole in the dies. Fig. 5 is a perspective view of the sole flanged in accordance 25 with my invention. Fig. 6 is a sectional view of the last, upper, and sole in position ready for sewing. Fig. 7 is a perspective view showing the line of stitches uniting the flange 30 of the sole and the upper. Fig. 8 is a sectional view similar to Fig. 6, showing the flange and upper sewed together and the flange turned down upon the sole. Fig. 9 is a sectional view of the shoe after it is turned and provided with an insole. Figs. 10, 11, 35 and 12 are diagrams illustrating one method of bending the flange of the sole; and Figs. 13, 14, and 15 are diagrams illustrating another method.

Referring in the first instance to Figs. 2, 3, 40 4, and 5, I would state that the main feature of my invention is the flanged sole A, which is cut out in the first instance, as shown in Fig. 2, of sufficient size to enable the flange a to be formed thereon and is skived or beveled 45 around the edge, as clearly shown in the enlarged view, Figs. 10, 11, and 12. After the sole is cut and skived it is bent on the line x, Fig. 11, in a suitable die or mold, clearly shown in Fig. 4, in which B represents the 50 former corresponding to the outline of the sole. On this former is placed the sole A to be flanged and over the sole is then passed

the die B', which may be made in any suitable manner so as to turn the skived edges of the sole over upon the former. Hence 55 when the sole is released from the dies it is in the form shown in Fig. 5, having an upturned flange a. The sole A is then secured to the last C, the means employed for this purpose in the present instance being a plate c, which is 60 secured to the last by a couple of sole-tacks c', common in shoe-making. Over the last is placed the upper D, which is wrong side out, and is preferably lined, as shown in Fig. 7, and when in position, as in Fig. 6, a row of 65 stitches d is made on the line y, Fig. 6, preferably at a point above the corner x, thus securely confining the upper to the flange of the sole. The next step is to secure to the sole that portion of the flange a which has heretofore 70 been at right angles to the body of the sole, and this is done by pressing the flange down upon the body, as shown in Fig. 8, and securing it either by cement or by any other suitable means. Thus it will be seen that the 75 stitching securing the sole to the upper is concealed between the flange and the sole, so that when the shoe is turned to expose the sole, as shown in Fig. 9, the stitches are concealed. By flanging the sole and turning down 80 the flange, the body of the sole is rounded, as clearly shown in Figs. 1, 9, 12, and 15, giving an exterior finish to the shoe without further manipulation, and an insole or lining can be placed in the shoe in order to give the 85 desired finish to the interior of the same. Where thin soles are used—such, for instance, as the soles of infant's shoes or other light shoes—the flange may be made as shown in Figs. 10, 11, and 12, the flange being bent up 90 on the line x, Fig. 11, beyond the skived portion, so that when the flange is turned, as shown in Fig. 12, it will have the appearance of a comparatively heavy sole; but where a thick sole is used, as shown in Figs. 13, 14, 95 and 15, I prefer to skive the edges, as shown in Fig. 13, and I bend the skived portion on the line x', Fig. 14, so that after the sole has been secured to the upper and the flange turned the rounded edge will be of the same 100 thickness as the body of the sole, as clearly shown in Fig. 15.

By the employment of a flanged sole in the manner described I am enabled to cheaply

manufacture a turned shoe that will be comfortable to the wearer, and at the same time will have a neat appearance without that elaborate preparation which has heretofore 5 been customary in making shoes of this class. The plate *c* (which I prefer to make of metal) not only tends to hold the sole to the last, but, being of the same contour as the last and sole, also acts as a guide in stitching the upper to 10 the flange of the sole. The flange *a* may, if desired, be formed on the sole after the same is applied to the last; but the preliminary formation of the flange is preferred.

I claim as my invention—

- 15 1. The mode herein described of making shoes, said mode consisting in turning up the entire substance of the sole near the edge to form a projecting flange, stitching the upper to said flange, folding the flange and upper 20 inward upon the body of the sole, and finally turning the shoe, substantially as specified.
- 25 2. The mode herein described of making shoes, said mode consisting in first skiving the sole at the edge, then turning up the entire substance of the sole near the edge to form a projecting flange, stitching the upper to said flange, folding the flange and upper inward 30 upon the body of the sole, and finally turning the shoe, substantially as specified.
- 30 3. The mode herein described of making

shoes, said mode consisting in turning up the entire substance of the sole near the edge to form a projecting flange, securing said sole to the last, applying the upper to the last, stitching said upper to the projecting flange 35 of the sole, folding the flange and upper inward upon the body of the sole, removing the shoe from the last, and finally turning the shoe, substantially as specified.

4. A shoe having the upper stitched to the sole adjacent to the edge of the same and having the entire substance of the sole with the attached portion of the upper folded inward at the edge, said folded portion being secured to the body of the sole, substantially as specified. 45

5. A shoe having a sole with skived edge and an upper stitched to said skived edge of the sole, the entire substance of the sole with the attached portion of the upper being folded 50 inward at the edge and said fold being secured to the body of the sole, substantially as specified.

In testimony whereof I have signed my name to this specification in the presence of 55 two subscribing witnesses.

DAVID BAINBRIDGE.
